UNITED STATES PATENT OFFICE.

ALBERT J. VITS, OF MANITOWOC, WISCONSIN.

DESIGN FOR A SYRUP-JUG.

57,486.

Specification for Design.

Patented Apr. 5, 1921.

Application filed August 4, 1919. Serial No. 315,329. Term of patent 14 years.

To all whom it may concern:

Be it known that I, ALBERT J. VITS, a citizen of the United States, residing at Manitowoc, in the county of Manitowoc and State of Wisconsin, have invented a new, original, and ornamental Design for a Syrup-Jug, of which the following is a specification, reference being had to the accompanying drawing, forming a part thereof.

The figure is a perspective view of the syrup jug showing my new design.

I claim:

The ornamental design for a syrup jug, as shown.

ALBERT J. VITS.
